US0D1027655S

(12) **United States Design Patent** (10) **Patent No.:** **US D1,027,655 S**
(45) **Date of Patent:** **** May 21, 2024**

(54) **CONTAINER**

(71) Applicant: **Runway Blue, LLC**, Alpine, UT (US)

(72) Inventors: **David O. Meyers**, Layton, UT (US);
John R. Omdahl, II, Lindon, UT (US)

(73) Assignee: **Runway Blue, LLC**, Alpine, UT (US)

(**) Term: **15 Years**

(21) Appl. No.: **29/869,312**

(22) Filed: **Dec. 28, 2022**

Related U.S. Application Data

(63) Continuation of application No. 29/760,741, filed on Dec. 3, 2020, now Pat. No. Des. 974,116.

(51) **LOC (14) Cl.** **09-01**

(52) **U.S. Cl.**

USPC **D9/549**; D7/510

(57) **CLAIM**

The ornamental design for a container, as shown and described.

DESCRIPTION

FIG. 1 is a top front isometric view of a container showing the claimed design;

FIG. 2 is a bottom rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures show portions of the container that form no part of the claimed design.

1 Claim, 7 Drawing Sheets
